(57) **CLAIM**

The ornamental design for a connecting member for electronic washing and drying machine, as shown and described.

DESCRIPTION

FIG. 1 is a front perspective view of the connecting member for electronic washing and drying machine showing our new design;

FIG. 2 is a front view thereof;

FIG. 3 is a back view thereof;

FIG. 4 is a left side view thereof where the right side view is a mirror image;

FIG. 5 is a top view thereof;

FIG. 6 is a bottom view thereof; and,

FIG. 7 is a front left perspective view of the connecting member for electronic washing and drying machine showing the state of use with the claimed design attached, connecting the washer and drying machine.

The broken lines showing of the washer and drying machine in FIG. 7 is for the purpose of illustrating environmental structure and form no part of the claimed design. All other broken lines shown in the figures depict portions of the connecting member for electronic washing and drying machine that form no part of the claimed design.
